UNITED STATES PATENT OFFICE.

FRANCIS JOSEPH McMURDIE, OF DETROIT, MICHIGAN, ASSIGNOR TO AMERICAN BLOWER COMPANY, OF DETROIT, MICHIGAN, A CORPORATION OF MICHIGAN.

VENTILATING APPARATUS.

1,019,818.

Specification of Letters Patent. Patented Mar. 12, 1912.

Application filed October 21, 1909. Serial No. 523,851.

To all whom it may concern:

Be it known that I, FRANCIS JOSEPH McMURDIE, a citizen of the United States of America, residing at Detroit, in the county of Wayne and State of Michigan, have invented certain new and useful Improvements in Ventilating Apparatus, of which the following is a specification, reference being had therein to the accompanying drawings.

10 The invention has particular reference to a window ventilating apparatus of the portable type, so constructed that the direction of the air current may be shifted at will so as to permit fresh air being admitted 15 directly into the room or discharged therefrom, as may be desired.

The invention consists in the novel and simple construction of the apparatus, in the 20 peculiar arrangement and combination of parts, and in certain details of construction, as will be hereinafter set forth.

In the drawings,—Figure 1 is a perspective view of an embodiment of my invention; Fig. 2 is an enlarged view in cross 25 section of the outer end of the apparatus, showing the application of the air filter; Fig. 3 is a perspective view of the current-directing mechanism; Fig. 4 is a detached perspective view of one of the cup members; Fig. 5 is an enlarged sectional view 30 taken on line $\alpha-\alpha$ of Fig. 1; and Fig. 6 is a detached perspective view of the filter.

In the drawings thus briefly described, A 35 represents the casing of the apparatus, comprising an inner section B substantially rectangular in form and adapted to rest upon the window sill, an intermediate section C designed to project beneath the window sash and outwardly therefrom, and an outer end 40 section D substantially rectangular in form having its bottom portion cut away preferably entirely, forming a passageway E for the entrance or discharge of the air. This outer section is also provided with a swinging door F at its outer end adapted to swing 45 outwardly, but held against inward movement for a purpose hereinafter set forth.

For forcing the air through the box I 50 employ a fan G of any suitable type and a motor H, and support these preferably upon a standard I rigidly attached to the section B of the casing.

J represents an intake pipe or conduit 55 leading from the fan downwardly to the air

box and communicating with the interior of the latter through its top, as plainly shown in Fig. 1.

K is a similar pipe or duct leading upwardly from the box at a point adjacent the 60 pipe J to the fan casing, forming the discharge conduit.

Within the interior of the box and arranged beneath communicating with the intake and discharge pipes respectively are 65 cup-shaped members L and M, each having a portion of its side wall cut away to form a lateral passageway or opening, as O, the remaining portion of the side wall being imperforate and the section of the wall opposite the opening slanting upward. Each member is provided with an annular flange or collar, as P, which extends upwardly through the casing top within a complementary collar or flange, as Q, which forms 70 a part of the casing, and the collar surrounding the intake conduit is circumferentially slotted, as at a, to permit of the extension therethrough of an operating handle b 75 fixed to the cup.

The cup members described are mounted side by side upon the casing bottom for horizontal rotation, and are provided each, with a gear wheel, as c, which gears intermesh. The space between the cup members and the sides of the casing is closed by means of filler blocks d e, and said members are arranged in close proximity so that the adjacent portions of their side walls abut the blocks and cup members forming in effect 80 a partition extending transversely within the front section of the air box, and being substantially imperforate except for the openings O.

Arranged within the outer section D of 85 the air box is an air filter R. This is preferably composed of a four-sided box S, open at the top and bottom, and a strip T of filtering material, such as cheese-cloth, which is drawn over two series of rods f g at the top and bottom portions of the box S and attached at its ends to the box sides. The filter is designed to have a sliding fit within the section D of the air box, so as to be readily removed and replaced when desired.

The forward end of the air conduit is provided preferably with a spaced pair of forwardly-extending ears or lugs U, and pivoted between these lugs is a deflector plate V, by means of which the draft of

air issuing from the air box may be caused to pass downwardly in relation to the box or upwardly, as may be desired.

In the operation of the mechanism the 5 motor is operated preferably by electricity, causing the fan to revolve and to discharge air through the box. If it is desired to have the air pass directly within the room from the outside, the cup members are shifted 10 through the agency of the handle *b* so that the openings *O* in the members *L* and *M* communicate with the box respectively in the rear and in front of the partition extending transversely of the box—formed by 15 the members *d*, *e*, *M* and *L*. Thus, air is drawn through the opening *E* and discharged into the room from the forward end of the air conduit. To reverse the direction of air the inlet *J* is placed in communication with the portion of the box in 20 front of the transverse partition and the discharge conduit *K* in communication with the box in rear of the transverse partition. This reversal is accomplished by moving 25 the handle *b* so as to rotate the cup members through an arc of substantially 180°, thereby positioning the openings of the members *L* and *M* respectively in front and in rear of the transverse partition. The air will 30 then be discharged from the rear of the box.

The air passing through the apparatus into the room necessarily passes through the screen or air filter, and is thereby cleansed, while the discharged air passes outwardly 35 through the opening controlled by the door *F*, operating automatically to allow of the discharge and closing when air is entering the conduit, to cause its passage through the filter.

40 1. What I claim as my invention is,—

1. In ventilating apparatus, the combination with a casing having inlet and outlet openings, of an air propelling device, intake and discharge ducts leading from said 45 device to the casing interior, relatively movable members within the casing formed each with an air passage, the passages registering with the air ducts and leading in different directions, and means for shifting the members 50 to change the position of the air passages and the direction of travel of the air current through the casing.

2. In ventilating apparatus, the combination with a casing having inlet and outlet 55 openings, of an air propelling device, intake and discharge pipes leading from said device within the casing, relatively movable members within the casing formed each with an air passage, the passages registering with the air ducts and being substantially oppositely disposed, a drive connection between the members, and a single operating device for operating the members simultaneously.

3. In ventilating apparatus, the combination 60 with a casing provided with openings

for the intake and discharge of air, of a blower, complementary air ducts leading from the blower to the casing interior, and rotatable cup members within the casing registering with the air ducts and formed each with a lateral discharge passage, the passages being substantially oppositely disposed.

4. In ventilating apparatus, the combination with a casing provided with intake and discharge openings, of a blower mounted upon the casing, intake and discharge pipes leading from the blower to the casing top and communicating with the casing interior, rotatable cups within the casing registering with the air ducts and formed each with a lateral discharge passage, the passages being oppositely disposed, a gear connection between the cups, and an actuating member operable from without the casing 85 for shifting the cups.

5. In a ventilating apparatus, the combination with the air box open at opposite ends, of a fan casing positioned without the box, inlet and outlet conduits communicating at opposite ends respectively with the fan casing and the conduit, and rotatable means controlling the ends of said conduit communicating with the casing for reversing the direction of travel of the air current 95 through the box.

6. In a ventilating apparatus, the combination with the air box open at opposite ends, of a fan casing positioned without the box, inlet and outlet conduits communicating at opposite ends respectively with the fan casing and the conduit, rotatable means positioned within the box for controlling the ends of said conduits communicating with the box, and means without the box for adjusting said rotatable means.

7. In a ventilating apparatus, the combination with an open ended casing, of mechanism for forcing a current of air through said casing, a filter within one of the casing ends, and a swinging door arranged above said filter, and positioned at said casing end, and adapted to be automatically opened by the current of air forced through the casing.

8. In a ventilating apparatus, the combination with an open ended casing, of mechanism for forcing a current of air through said casing, means for reversing the direction of the current through the casing, a filter within one of the casing ends, and a swinging door adjoining the filter automatically opened by the current of air in one direction of travel of the latter and automatically closed upon the reversing of the direction of the air current.

9. In a ventilating apparatus, the combination with an air box having inlet and outlet passages, of a partition intermediate said passages dividing the box into complementary chambers, and a fan provided with in-

take and discharge openings communicating respectively with said complementary chambers, said partition including rotatable means for alternating communication between the intake and discharge openings and said complementary chambers.

10. In a ventilating apparatus, the combination with an air box having inlet and outlet passages, of a partition intermediate said passages dividing the box into complementary chambers, and a fan provided with intake and discharge openings communicating respectively with said complementary chambers, said partition including relatively rotatable members for alternating communication between said intake and discharge openings and said complementary chambers.

11. In a ventilating apparatus, the combination with an air box having inlet and outlet passages, of a partition intermediate said passages dividing the box into complementary chambers, and a fan provided with intake and discharge openings communicating respectively with said complementary chambers, said partition including

relatively rotatable members for alternating communication between said intake and discharge openings and said complementary chambers, and an operating member extending without the box for simultaneously adjusting said rotatable members.

12. In a ventilating apparatus, the combination with an air box having inlet and outlet passages, of a partition intermediate said passages dividing the box into complementary chambers, a fan mounted upon the box provided with intake and discharge ducts leading within the box and communicating respectively with said complementary chambers, said partition including relatively rotatable members for alternating communication between said intake and discharge ducts and said complementary chambers, and means extending without the box for adjusting said rotatable members.

In testimony whereof I affix my signature in presence of two witnesses.

FRANCIS JOSEPH McMURDIE.
